UNITED STATES PATENT OFFICE.

JAMES TIMMS, OF COLUMBUS, OHIO.

DESIGN FOR A CAR-CO尤LING KNUCKLE.

SPECIFICATION forming part of Design No. 29,447, dated October 4, 1898.

Application filed September 6, 1898. Serial No. 690,342. Term of patent 14 years.

To all whom it may concern:

Be it known that I, JAMES TIMMS, a citizen of the United States, residing at Columbus, in the county of Franklin and State of Ohio, 5 have invented and produced a new and original Design for Knuckles for Car-Couplings, of which the following is a specification, reference being had to the accompanying drawing, forming part thereof.

10 The accompanying drawing is a view in perspective of my new design of knuckle.

As shown in the drawing, the leading or material feature of my design consists of a car-coupling knuckle having two oppositely-disposed inclines 1 and 2, located adjacent to the 15 free end of the tongue, and a smooth or plain

surface 3 intermediate the two inclines. The rear incline 2 is formed partly on an extension 4 of the tongue A and is more extensive and of greater length than the incline 1. 20

The rear front edge of the tongue A is provided with the rib 5, which latter, as clearly shown, is located at the base of incline 1.

Having described my invention, what I claim as new, and desire to secure by Letters 25 Patent, is—

The design for a car-coupling knuckle, as herein shown and described.

JAMES TIMMS.
